UNITED STATES PATENT OFFICE.

HORN G. DONIGAN, OF ST. LOUIS, MISSOURI.

EXTENSIBLE TOWER.

1,092,096.

Specification of Letters Patent. Patented Mar. 31, 1914.

Application filed October 6, 1911. Serial No. 653,167.

To all whom it may concern:

Be it known that I, HORN G. DONIGAN, a citizen of the United States, residing at the city of St. Louis, State of Missouri, have 5 invented certain new and useful Improvements in Extensible Towers, of which the following is a specification, reference being had therein to the accompanying drawings.

The present invention has reference to 10 extensible towers, and relates more particularly to a tower which carries a platform at its top to support fire fighters.

The invention is particularly designed for 15 mounting upon a movable base, preferably a motor car, or truck, and embodies supplemental supports which are projected toward and from the burning building, and which are braced against vibration due to the passage of the water through the hose.

20 The invention further embodies means for bracing the tower and maintaining the vehicle against movement throughout the time that the tower is connected to a building and during the raising and lowering 25 movements of the tower.

A structural embodiment of the invention is illustrated in the accompanying drawings, whereof:

Figure 1 is a plan view of the tower 30 mounted upon a vehicle and designed for use as a fire-apparatus; Fig. 2 is a side elevation of Fig. 1, the tower being shown in both figures as in its lowered position; Fig. 3 is a side elevation, showing the tower in elevated position and as connected at its top to a building; Fig. 4 is an enlarged plan view, partly in section, of the body of the 35 vehicle, showing the mechanism for elevating the tower and the connection of the main hose with said tower; Fig. 5 is a transverse vertical sectional view of Fig. 4; Fig. 6 is a detail view showing the mounting of the guy-ropes employed for bracing the tower, and the vehicle-retaining device; and Fig. 7 40 is an enlarged side elevation of the tower in its lowered position.

45 Referring to said drawings, the improved tower, which is indicated generally by the numeral 1, is depicted as mounted upon a movable base, here shown as constituted by a suitable vehicle, preferably a motor car

or truck, designated by the numeral 2. The tower proper consists primarily of a series of nested or telescoped cylindrical shells 3, arranged in stepped relation within one 55 another, the outermost, or lowest shell being provided at its lower end with a ring or collar 4 that is fastened to a bed 5 secured, in turn, to the floor 6 of the car. At its upper end, each cylinder is provided with a 60 collar 7 which supports the collar on the next inner cylinder. The upper end of the innermost cylinder is continued upward to a slight extent, and is fastened to a plate 13.

To raise and lower the tower, a pair of 65 lazy-tongs 14 are preferably provided. These elements are arranged upon opposite sides of the tower, and their component levers 15 are arranged and connected with each other in the usual manner. The free ends of the 70 uppermost levers of each lazy-tong are connected with depending lugs 16 provided upon plate 13, and those of the lowermost levers are connected to blocks 17 slidable in guides 18 mounted upon base 6. The adjacent ends of the corresponding levers of the two series or sets are connected by tubular rods 19, on which, in turn, are rotatably mounted sockets 20 that receive the lower 75 ends of pairs of cross-braces 21. These 80 braces are slidably connected adjacent their upper ends with rotatably mounted double-sleeves 22 that are carried by trunnions 23 provided upon the cylinder collars 7, the said brace ends being equipped with nuts 85 24 which serve to limit the upward movement of the cylinders.

The lazy-tongs are operated by moving the pairs of blocks 17 toward and from each other, this being preferably effected by providing said blocks with threaded axial openings through which extend the threaded ends 25 of a pair of horizontal shafts 26, the arrangement being such that upon rotation of either shaft the two blocks mounted thereon will be caused to approach or recede from each other according to the direction in which the shaft is rotated. Shafts 26 are themselves rotated in unison from the main drive shaft 27 through the agency of intermeshing worm gears 28 and 29, the last-mentioned shaft being journaled in brackets 90 95 100

30 mounted on base 6, and being driven either manually or from the engine by means of suitable transmission gearing.

In addition to the braces 21, there is further provided, for the purpose of steadyng the tower against sidewise swaying movement, when elevated, a pair of guy-ropes 31 which are attached at their upper ends to eyes 32 secured to plate 13, the lower ends 10 of these ropes being wound upon drums 33 carried by depending spindles 34 connected to base 6, as depicted in Fig. 5. Intermediate their passage from the drums to the plate eyes, the said ropes are led through the 15 hollow lower members 35 of angular braces 36 that are pivotally connected at their ends with the opposite side members 37 of the frame or chassis of the car, said braces being provided at their apices with guide pulleys 20 38 and with depending angular brackets 39. The frame sides are apertured, as indicated by the numeral 40 in Figs. 5 and 6, to permit the ropes to be led to the hollow brace members 35 from the drums, and the latter, in 25 turn, are provided with bevel gears 41 which mesh with similar gears 42 fast on shaft 27. Shaft 27 carries a ratchet wheel 43 which is engaged by a pawl 44, said pawl being disengaged manually or otherwise, from said 30 ratchet while the tower is being raised, and is reengaged therewith when the tower has been elevated to the desired extent so as to check any tendency of the ropes to unwind from their drums when the tower sways to 35 either side.

The afore-mentioned side braces 36 are disposed adjacent to and parallel with the frame sides 37 during the time that the car is being driven to or from a fire, and are 40 held in such position by means of suitable latches 45 which are carried by the car and are designed to engage clamp screws 46 revolubly mounted on the horizontal lower arms of the brackets 39. When the tower is 45 to be raised, however, these braces are swung outwardly to a position at right-angles to the frame sides, and their screws 46 are tightened against the ground, so as to prevent the car from tipping toward either side.

50 Plate 13 at the top of the tower proper serves to support a turn-table 47 on which latter there is mounted the main platform 48, a series of roller-bearings 49 being interposed between said turn-table and a stationary circular rack 50 that is secured directly upon the upper face of said plate. To rotate said platform relative to the tower there is provided a pinion 51 carried by a vertical shaft 52, which shaft is secured to the platform 60 and is furnished with a hand-wheel 53 or similar operating element. The platform is equipped at opposite sides with rails 54 and is extended slightly toward the opposite ends of the car, as indicated by the numeral

55; it normally occupies the position illustrated in Fig. 1, and is held against rotation from such position by any suitable devices, as, for example, a pin 56 which is removably inserted in registering perforations, (not shown), in the platform, turn-table and 70 rack.

Access to the platform is afforded by means of a rope ladder 57 connected thereto at its upper end, the lower portion of the ladder being coiled up or laid underneath 75 one of the seats in the back part of the car. When the tower structure is lowered, the tubes 19 that connect the ends of the lazy-tong levers 15 may also be used to gain access to the platform, these tubes themselves 80 constituting ladders, as it were.

The water for fighting the fire is supplied to the main hose 58, from any suitable source or sources by way of a cross-pipe 59 provided with a central inlet connection 60, and 85 at each end with a series of outlet connections 61. The inlet 60 is designed for connection with the rear end of hose 58, which latter, when not in use, may be laid or coiled up in the back part of the car in the usual 90 manner, but which, when about to be used, is led through an opening 62 in bed 5 into and through the interior of the hollow tower structure, and through a passage 63 at the top of the tower produced by registering openings in the parts 13, 50, 47 and 48. Upon the platform 48 is pivotally mounted, by means of a yoke 64 with which it is provided, a nozzle 65, to which the upper end of hose 58 may be connected. In addition, to the 100 main hose 58, there may be provided a supplemental hose 66 which is connected to a chemical tank 67 supported in any desired manner upon the car, and is led upwardly, from a receptacle 68 wherein it is normally 105 coiled, between a pair of rollers 69 carried by a bracket 70 secured to platform 48; the nozzle at the upper end of this hose is normally engaged by a clamp 71 attached to one of the platform rails 54.

110 The arrangement of the two hose is such, therefore, that both will be gradually raised with the platform, when the latter is being elevated, by reason of their connection thereto, and, when said platform has been raised to the required height, the nozzle of the chemical hose may be readily released from clamp 71 and that hose taken into the burning building, if desired, as hereinafter described, the passage of said hose between the 115 rollers 69 facilitating its being drawn into the building.

In order to enable the fire-men to enter the building, and, also, to permit the occupants of the building to escape therefrom onto the main platform 48, one or more supplemental platforms 72 may be provided, two of such platforms being utilized in the 125

construction illustrated wherein they are shown as located directly in line with the extensions 55 of the main platform. They are preferably in the form of extensible 5 booms, each constituted by side and bottom pairs of lazy-tongs 73 and 74. The side lazy-tongs 73 occupy parallel vertical planes, and their component levers 75 are connected with each other at intervals by 10 horizontal cross-rod 76. To extend or retract each boom, there is provided a centrally-fulcrumed lever 78 mounted upon the corresponding extension 55 and connected through the agency of a link 79 with the adjacent lazy-tongs 73, a suitable detent mechanism 80 being provided to hold the lever in adjusted position.

From the foregoing it will be understood that when the car has reached the scene of 20 the fire, the main platform may be raised to the height necessary to bring it approximately on a line with one of the windows in the burning building, after which, said platform may be rotated in the manner herein-

25 above described to aline either of its supplemental platforms with that window, the supplemental platform being subsequently extended toward the window. As further regards the several platforms with which the 30 tower is provided, it may be stated that when the supplemental platforms are in their normal or retracted position, the combined length of said supplemental platforms and the main platform is approximately 35 equal to that of the car. On the other hand, when both supplemental platforms are fully extended, their outer ends will reach to the buildings upon opposite sides of the street, in case it becomes necessary to extend both 40 platforms in such manner. The tower itself is normally of such a height as to permit it to pass without obstruction beneath the trolley wires when the car is running to or from a fire. An endwise movable rod 81 is slid-

45 ably supported in a pair of sleeves 82, which latter are swiveled to sleeves that underlie the sleeves 82 and are slideable endwise along the rail 54, which latter is of arc-shape. The rod 81 performs a dual function, namely, it 50 steadies the tower against vibrations set up by the passage of the water through hose 58, and it also provides a hand rail for the supplemental platforms 72. The outer end of this rod carries a clamp comprising fixed 55 and movable jaws 83 and 84, the latter of which is slideable longitudinally of the rod and is held in adjusted position by means of a pin 85 adapted for interchangeable engagement in a series of apertures 86 formed 60 through the rod. Arm 84 is further provided with a clamp-screw 87 which affords a means for firmly securing the rod to the sill of a window in the manner depicted in Fig. 3. The rod itself is held in adjusted po-

sition through the agency of set-screws 88 65 borne by the sleeves 82.

The operation of the invention is believed to be obvious from the foregoing and to require, in consequence, no separate description, it being apparent that upon rotation 70 of the drive shaft 27 in the proper direction, the lazy-tongs 14 will be extended through the agency of the gear connections 29 and 28 between that shaft and the two block shifting shafts 26, and will raise up the main 75 platform, which latter is supported and held against swaying movement by the braces 21 and the guy-ropes 31, and, in addition, by the adjustable clamp rod 81. When the platform is raised, it carries with it the main 80 and auxiliary hose 58 and 66, and, also, the rope ladder 57. On reaching the required height the platform may be turned in the proper direction and the auxiliary platforms then extended. The car itself is steadied 85 by swinging the angular braces 36 into operative position and subsequently lowering the ground clamps 46.

What is claimed is:

1. In combination with a rotatable plat- 90 form, an arc-like horizontal rail rigidly supported thereon, a pair of spaced sleeves slidably mounted on the rail for movement longitudinally of the rail, superposed sleeves swiveled to the first named sleeves, a rod 95 movable endwise through said second named sleeves and provided at its outer end with a clamp adapted for engagement with the wall of a building, and means to hold the rod in adjusted position.

2. In combination with an extensible tower, and means for actuating the tower, a movable base for the tower, a pair of V-shaped braces arranged on opposite sides of the base, means for pivoting the free end 105 of the upper leg to said base, means at substantially right angles to the lower leg for pivoting the latter to the base whereby to allow movement of the braces into position at right angles to said base, the lower leg of 110 each brace being hollow, a pulley connected to the apex of each brace to substantially aline with the interior of the lower leg, guy-ropes connected at one end to the top of the tower and being led around said pul- 115 leys and passed through the hollow lower legs of said braces, means for winding the other end of each rope, means to operate the winding means in unison, and ground en- 120 gaging means connected to the apices of said braces.

3. In combination with an extensible tower having a main rotatable platform at the top thereof, and a supplemental plat- 125 form connected to the main platform and extensible endwise therefrom, an endwise adjustable rod overlying the supplemental platform and extending parallel therewith

and having a clamp at its outer end for engagement with a window or the like, a support on the main platform to which said rod is adjustably connected, means for holding said rod in adjusted position on said support, and means for rotating the main platform to direct the supplemental platform and said rod toward the window or the like,

the rod providing a hand rail for the supplemental platform.

In testimony whereof I hereunto affix my signature in the presence of two witnesses.

HORN G. DONIGAN.

Witnesses:
